[57] CLAIM

The ornamental design for a leg splint for horses, as shown and described.

DESCRIPTION

FIG. 1 is a left side elevational view of a leg splint for horses showing my new design, with the leg securing straps closed;

FIG. 2 is a rear perspective view thereof, showing the securing straps in open positions;

FIG. 3 is a right side elevational view thereof, with the securing straps removed for convenience of illustration;

FIG. 4 is a rear elevational view of FIG. 3;

FIG. 5 is a front elevational view of FIG. 3;

FIG. 6 is a top plan view of FIG. 3; and

FIG. 7 is a bottom plan view of FIG. 3.

The fragmentary broken line representation of a horses leg in FIG. 1 is for purposes of illustration only.
